UNITED STATES PATENT OFFICE.

GEORGE COE ACKER, OF JACKSONVILLE, FLORIDA.

ATTACHMENT FOR LOCOMOTIVES.

1,308,467.

Specification of Letters Patent.

Patented July 1, 1919.

Application filed September 19, 1918. Serial No. 254,738.

To all whom it may concern:

Be it known that I, GEORGE C. ACKER, a citizen of the United States, and a resident of Jacksonville, in the county of Duval and 5 State of Florida, have invented certain new and useful Improvements in Attachments for Locomotives, of which the following is a specification.

My invention is an improvement in attachments for locomotives, and has for its 10 object to provide a new and improved shoe and wedge for locomotive driving boxes, wherein the shoe and wedge are steel, with an interchangeable cuff or facing of brass or 15 bronze on the wearing surface to permit the replacement of the cuff or facing when worn, without requiring a new shoe or wedge.

In the drawings:

Figure 1 is a sectional view through a 20 driving box provided with the improved shoe and wedge;

Fig. 2 is a section on the line 2—2 of Fig. 1, looking in the direction of the arrows adjacent to the line;

25 Fig. 3 is a perspective view of the wedge;

Fig. 4 is a similar view of one of the cuffs or facings;

Fig. 5 is a vertical section through the device;

30 Fig. 6 is a similar view through the shoe.

In the present embodiment of the invention, the improvement is shown in connection with the driving box 1 of a locomotive, the said box being mounted in the usual 35 frame 2. The shoe 3 and the wedge 4 are arranged between the driving box and the sides of the opening for the box in the usual manner, the shoe being at one side and the wedge at the other, and it will be noticed 40 that both wedge and shoe are channel shaped, the inner wall of the bottom of the wedge being inclined as shown.

That wall of the opening 5 in the frame 45 for the driving box with which the wedge coöperates is also inclined, as indicated at 6, and by means of a set screw 7 having lock nuts 8 the wedge may be moved vertically to compensate for wear, being moved inwardly toward the driving box as it is moved upwardly.

As is known, brass provides the most satisfactory bearing in constructions of this character, but a large amount of brass is required for wedges and shoes of this character. With the present invention the body 55 and larger portion of both wedge and shoe

are of cast steel, which will last indefinitely, while the wearing surfaces only are of brass or bronze.

As shown, both wedge and shoe, which are 60 the same so far as the bearing surface or facing of bronze is concerned, are cut away on the outer faces of their bottom and side walls, as indicated at 9 and 10, respectively, and the ends of the cut away portion 10 on 65 the side wall are rabbeted or cut away, as indicated at 11.

The cuff or facing of bronze or brass shown in Fig. 4 is also channel shaped, consisting of a bottom wall 12 and side walls 70 13, and the ends of the side walls are beveled as shown at 14, to fit the undercut ends 11 of the rabbets on the side walls. The ends of the bottom wall are square, and it will be evident that the cuff or facings may be 75 slipped on from the bottom wall of the wedge or shoe.

At the center of each side wall on the rabbeted surface there is a substantially triangular lug 15 having its base at the free edge 80 of the side wall and having its apex at about the center of the rabbeted portion, and the side walls of the facings or cuffs are notched, as indicated at 16, to fit these lugs.

I claim:

1. In a locomotive driving box, the combination with the box, of a shoe and a wedge arranged at opposite sides thereof between the same and the frame, both shoe and wedge being channel shaped and being cut away or 90 rabbeted on the outer face intermediate the ends to receive a lining or facing of alloy, said lining or facing and the wedge or shoe having means for holding the lining or facing in place.

2. A wedge or shoe for locomotive driving boxes having its outer face cut away or rabbeted intermediate its ends on the bottom and side faces, and a channel shaped cuff or facing seated in the rabbeted portions, the ends of the rabbeted portions at the sides of the shoe or wedge being undercut and the ends of the side wall of the facing being shaped to fit said undercut ends, the shoe or wedge having at each side wall intermediate 105 the ends of the rabbeted portion lugs, and the cuff or facing being notched to receive the lugs.

3. A wedge or shoe for locomotive driving boxes having its outer face cut away or rabbeted intermediate its ends on the bottom and side faces, and a channel shaped cuff or

facing seated in the rabbeted portions, the ends of the rabbeted portions at the sides of the shoe or wedge being undercut and the ends of the side wall of the facing being shaped to fit said undercut ends.

4. A wedge or shoe for locomotive driving boxes, and a channel shaped cuff or facing in

which the shoe seats, said shoe and cuff having means for holding them together.

GEORGE COE ACKER.
